(57) **CLAIM**

The ornamental design for a wooden handle grill brush, as shown and described.

DESCRIPTION

FIG. 1 is an isometric view of a wooden handle grill brush in accordance with the new design;

FIG. 2 is a side view thereof;

FIG. 3 is a top view thereof;

FIG. 4 is a bottom view thereof;

FIG. 5 is an enlarged front view thereof; and,

FIG. 6 is an enlarged rear view thereof.

The elements shown in broken lines illustrate portions of the grill brush that form no part of the claimed design.
